HOLDER FOR CANS OR SIMILAR ARTICLE

James R. Coleman, Des Moines, Iowa, assignor of one-half to John Phillips

Application September 2, 1955, Serial No. 37,778

Term of patent 14 years

(Cl. D58—26)

Fig. 1 is a perspective view of a holder for cans or similar article;

Fig. 2 is a top plan view thereof; and

Fig. 3 is an elevational view thereof.

I claim:

The ornamental design for a holder for cans or similar article, as shown.
